Patented July 20, 1971

221,261

UNDERWATER TOWING APPARATUS

Eugene J. Tallarico, 173 Bleecker St.,
New York, N.Y. 10012

Filed Mar. 5, 1970, Ser. No. 21,754

Term of patent 14 years

Int. Cl. D21—03

U.S. Cl. D71—1

FIG. 1

FIG. 3

FIG. 4

FIG. 2

FIG. 5

FIG. 6

FIG. 1 is a top view of underwater towing apparatus showing my new design;

FIG. 2 is a bottom view thereof;

FIG. 3 is a rear view thereof with portions of the screen in the left of the figure deleted for clarity of illustration;

FIG. 4 is a front view thereof;

FIG. 5 is a side view thereof; and

FIG. 6 is an enlarged fragmentary view of the propeller guard and connection as seen in FIG. 4 with the screen removed for clarity of illustration.

I claim:

The ornamental design for an underwater towing apparatus, as shown and described.
